UNITED STATES PATENT OFFICE.

NATHANIEL MCNAIR, OF VANCOUVER, BRITISH COLUMBIA, CANADA.

SHINGLE-DRYING KILN.

Application filed June 13, 1923. Serial No. 645,152.

To all whom it may concern:

Be it known that I, NATHANIEL MCNAIR, citizen of the Dominion of Canada, residing at Vancouver, in the Province of British Columbia, Canada, have invented certain new and useful Improvements in Shingle-Drying Kilns, of which the following is a specification.

This invention relates to an improvement 10 in shingle drying kilns, the improvements being directed to the abstraction of the moisture laden air from the kiln at a relatively low temperature whereby a more uniform heat is maintained throughout the stacks of 15 shingles being dried, whereby the shingles are more quickly and thoroughly dried and with a greater economy of heat.

These results are attained by a careful 20 consideration of the conditions prevailing in shingle drying kilns as at present constructed. In the present practice the bundles of cut shingles are loosely stacked on trucks, which are run into a substantially air-tight chamber heated by steam pipes 25 horizontally disposed immediately below the level of the track rails whereby the heated air rising from the steam pipes passes through the bundles of stacked shingles and evaporates the moisture from them.

While it is admittedly desirable to withdraw this moisture laden air from the chamber, great diversity of opinion exists as to what part of the chamber it should be drawn from. General opinion favours withdrawing 30 it from the upper part, which is now usually done by providing a series of ducts in the side walls of the chamber adjacent one end and at approximately half the height of the chamber, which ducts are connected to an uptake or chimney at one end, and air inlet ducts are provided in the lower part of the chamber at the opposite end.

While this practice is, to a certain extent, 45 satisfactory, the moisture laden air being withdrawn from the upper part of the chamber carries to waste a considerable amount of heat having further evaporative capacity. It also limits the level of relatively high temperature in the kiln chamber to above the exit aperture, as the moisture laden air falling down the sides of the chamber has, below the level of the withdrawal ducts, a temperature considerably lower than that above the ducts. This moisture readily

condenses on the surfaces of the shingles, 55 which are relatively cooler than the moisture laden air, and this condensed moisture has later to be re-evaporated from the shingles.

This condition is evidenced in the fact that in the customary kilns the lower bundles of 60 shingles are invariably much discoloured and the iron clasping bands are rusted; also in the fact that at the completion of the 65 drying process the weight of the shingles from the lower part of the stack is considerably greater than those from the upper part of the same.

These defects I have overcome in the kiln, 70 which is the subject of this application, by withdrawing the moisture laden air not from the upper part of the chamber, but from the lower part of the same, that is, from below the level of the steam heating pipes. The 75 withdrawal ducts have a considerably greater area than what is at present used, say twelve square feet of cross section area in a kiln of from twenty to thirty feet wide and one hundred and twenty feet long and fifteen to twenty feet in height. An approximately equal amount of external air is admitted at the end opposite the withdrawal ducts, which air admission is under complete control that it may be regulated to meet requirements.

With this arrangement the admitted air is 85 heated as it passes upward between the steam pipes, and passing through the stacks of shingles evaporates moisture from them. As this moisture laden air cools it descends 90 the sides of the chamber and may again circulate upward past the steam pipes and the shingles but such of it as is fully saturated with moisture being cooler and heavier, will pass below the steam pipes to the bottom of the chamber and is withdrawn 95 at the further end.

The admission being at one end and the withdrawal at the other end causes a progressive flow through the chamber during its ascent through the shingles, while hot, 100 and its descent down the sides of the chamber as it cools.

By this means the temperature of the chamber is maintained reasonably uniform 105 throughout the depth of the stacks of the shingle bundles and no air is withdrawn that has possibilities of further evaporation. This is evidenced in the fact that the

shingles are more fully dried in the same time and to a substantially uniform extent, and they are free from moisture discolouration and rust.

5 The invention is particularly described in the following specification, reference being made to the drawings by which it is accompanied, in which:

10 Fig. 1 is a longitudinal section of the kiln.

Fig. 2 is a sectional plan of the same, and

Fig. 3 is a cross section on the line 3—3 in Fig. 2 looking in the direction of the arrow, showing the charge of shingle bundles.

15 In these drawings 2 represents the side walls of the roofed kiln, 3 being the doors closing air-tight the entrance to the kiln, and 4 those closing the exit. Throughout the length of this kiln, track rails 5 are supported at an approximate height of five or 20 six feet from the bottom of it, and beneath these track rails a series of steam pipes 6 are carried lengthwise of the kiln from a transverse delivery header 7 to a transverse discharge header 8, the pipes 6 being at a 25 slight downward slope toward the discharge header 8 with a quick fall immediately adjacent the connection thereto, by which means the heating pipes 6 are maintained in close proximity to the shingle pack throughout the length of the kiln.

30 At the floor level, and therefore below the heating pipes 6 are apertures 10 beneath the exit doors 4, through which apertures air is admitted to within the chamber, which admission is controlled by dampers 11.

35 Across the opposite or entrance end of the kiln ample exit apertures 12 deliver into a transverse duct 13 and therefrom into two uptakes 14 for the delivery of moisture laden air from the chamber under natural draught. These uptakes 14 are not only 40 larger in area than is customary but are higher as the vapours conducted by them are relatively cooler than usual.

45 The bundles of shingles are, as at present, stacked loosely on low wheeled trucks 15, and are run into the chamber on the track rails 5 and with all doors closed air-tight, the air heated from the steam pipes 6 passes 50 upward through the interspaces of the stacked shingle bundles and evaporates the moisture therefrom. This moisture laden air rises to the top of the chamber and as it cools or is displaced by other rising moisture laden air it passes by convection down the side walls 2 of the kiln where it may 55 again be heated by contact with the steam pipes 6 and evaporate more moisture from the shingles, but the fully saturated and 60 cooler air will reach the lower part of the chamber below the steam pipes 6 and find its exit through the ducts 12 and transverse duct 13 to the uptakes 14.

65 The result is certainly advantageous, as a considerably higher temperature is main-

tained throughout the entire depth of the charge of shingles being dried, and evidence of any condensation of moisture on the lower shingles of the stack, which is very marked in the output of the usual shingle drying kiln, is entirely absent. The shingles are more completely dried for the same period of exposure, and the drying is more uniform throughout the depth of the stack.

70 I am aware that prior to my invention attempts have been made to withdraw the moisture laden air from the lower part of the kiln, but in all with which I am acquainted, the replacement air has been admitted above the steam pipes to the upper 75 part of the chamber and has been ineffective. Never within my knowledge has the air been admitted to a shingle drying kiln below the heating pipes at or near the bottom at one 80 end and withdrawn, when saturated with moisture, from approximately the same level at or adjacent the other end.

85 Obviously, the air withdrawn must be the coolest and be moisture laden.

90 Having now particularly described my invention, I hereby declare that what I claim as new and desire to be protected in by Letters Patent, is:

95 1. A drying kiln for shingles, comprising the combination with a substantially air-tight chamber having a heating means disposed along its length and width at a short distance from the bottom, means adjacent one end of the chamber for withdrawing 100 from below the heating means the moist vapors evaporated from the shingles, and means adjacent the opposite end of the chamber for admitting below the heating means external air for replacement.

105 2. A drying kiln for shingles, comprising the combination with a substantially air-tight chamber having steam heating pipes disposed along the length and breadth of the chamber at a short distance from the bottom thereof, withdrawal ducts at one end 110 of the chamber below the level of the steam heating pipes, said ducts communicating with an uptake, and ducts admitting external air to the chamber below the level of the heating pipes.

115 3. A drying kiln for shingles, comprising the combination with a substantially air-tight chamber having steam heating pipes disposed along the length and breadth of the chamber at a short distance from the bottom thereof, withdrawal ducts at one end of the chamber below the level of the steam heating pipes, said ducts communicating with an uptake, and ducts admitting external air to the chamber below the level of the heating pipes and remote from the withdrawal ducts, and means for controlling the amount of air admitted.

120 4. A drying kiln for shingles, comprising the combination with a substantially air-

tight chamber having steam heating pipes disposed along the length and breadth of the chamber at a short distance from the bottom thereof, withdrawal ducts at one end 5 of the chamber and substantially at the level of the bottom thereof, said ducts communicating with an uptake, and ducts at the op-

posite end of the chamber admitting external air to the chamber below the level of the heating pipes, and means for controlling the 10 amount of air admitted.

In testimony whereof I affix my signature.

NATHANIEL McNAIR.
